UNITED STATES PATENT OFFICE.

ANDREW J. SANFORD, OF NEWARK, OHIO, ASSIGNOR TO A. H. HEISEY & CO. INC., OF NEWARK, OHIO, A CORPORATION OF WEST VIRGINIA.

DESIGN FOR A JAR.

40,837.

Specification for Design. Patented Aug. 23, 1910.

Application filed May 28, 1910. Serial No. 564,301. Term of patent 14 years.

To all whom it may concern:

Be it known that I, ANDREW J. SANFORD, a citizen of the United States, residing at Newark, county of Licking, and State of Ohio, have invented a new, original, and ornamental Design for Jars, of which the following is a specification, reference being had to the accompanying drawing, forming a part thereof.

The drawing is a perspective view of a glass crushed fruit jar showing my new design.

The leading features of my design com-

prise a jar of general cylindrical shape provided with a lid of sloping shape terminating in a dome, the dome and jar body being ornamented with bands or borders of Grecian design.

I claim:

The ornamental design for a jar, as shown and described.
